(57) **CLAIM**

I claim the ornamental design for a grommet, as shown and described.

DESCRIPTION

FIG. 1 illustrates a front perspective view of a grommet according to the present invention;

FIG. 2 illustrates a rear perspective view of a grommet according to the present invention;

FIG. 3 illustrates a front elevation view of a grommet according to the present invention;

FIG. 4 illustrates a left side elevation view of a grommet according to the present invention;

FIG. 5 illustrates a right side elevation view of a grommet according to the present invention;

FIG. 6 illustrates a rear elevation view of a grommet according to the present invention;

FIG. 7 illustrates a top view of the grommet according to the present invention; and,

FIG. 8 illustrates a bottom view of the grommet according to the present invention.

The broken lines are included for illustrative purposes only and form no part of the claimed design.
